UNITED STATES PATENT OFFICE.

CHARLES C. WORTHINGTON, OF DUNNFIELD, NEW JERSEY.

DESIGN FOR A DUPLEX STEAM-CYLINDER CASING AND CRADLE.

SPECIFICATION forming part of Design No. 30,498, dated April 4, 1899.

Application filed March 10, 1899. Serial No. 708,612. Term of patent 14 years.

To all whom it may concern:

Be it known that I, CHARLES C. WORTHINGTON, a citizen of the United States, residing at Dunnfield, county of Warren, and State 5 of New Jersey, have invented and produced a certain new and original Design for a Duplex Steam-Cylinder Casing and Cradle, fully described and represented in the following specification and the accompanying drawings, 10 forming a part of the same.

This invention relates to a new and original design for a duplex steam-cylinder casing and cradle; and the invention consists in a 15 peculiar shape or configuration of the same, substantially as shown in the accompanying drawings, in which—

Figure 1 is a side view of a duplex steam-cylinder casing and cradle embodying the design. Fig. 2 is a plan view of the same. Fig. 3 20 is a perspective view of the same, looking from the steam-cylinder end.

The leading feature of the design is the peculiar shape and configuration of the structure, with the steam-cylinders A curving outward from the central steam-port portion B 25 thereon and developing into the cradle portions C, which terminate in the end plate D. The cylinders A are shown as formed with flanges E at their outer ends and with base-supports F, and the whole structure is shown 30 as forming a single casting.

What I claim is—

The design for a duplex steam-cylinder casing and cradle, substantially as shown and described.

In testimony whereof I have hereunto set my hand in the presence of two subscribing witnesses.

CHARLES C. WORTHINGTON.
